UNITED STATES PATENT OFFICE.

ELBERT B. McCLURD, OF ELIZABETHTON, TENNESSEE.

SEAT CONSTRUCTION FOR SEWING AND OTHER MACHINES.

1,395,130.

Specification of Letters Patent. Patented Oct. 25, 1921.

Application filed January 17, 1921. Serial No. 437,904.

To all whom it may concern:

Be it known that I, ELBERT B. McCLURD, a citizen of the United States, residing at Elizabethton, in the county of Carter and 5 State of Tennessee, have invented new and useful Improvements in Seat Constructions for Sewing and other Machines, of which the following is a specification.

My present invention has for its object 10 the provision of a seat construction for sewing machines and like machines, characterized by the capacity of being adjusted to conveniently position an operator for the working of the machine, and by the capacity 15 of being moved out of the way when not in use.

To the attainment of the foregoing, the invention consists in the improvement as hereinafter described and definitely claimed.

20 In the accompanying drawings, forming part hereof:—

Figure 1 is a view showing a sewing machine in side elevation and with my seat construction properly applied.

25 Fig. 2 is a front elevation of the same.

Fig. 3 is an enlarged detail section.

Fig. 4 is an enlarged detail side elevation showing one of the toothed shanks and the dog for coöperation therewith.

30 Fig. 5 is a transverse section on line 5—5 of Fig. 3.

Similar numerals of reference designate corresponding parts in all of the views of the drawings.

35 The main frame 1 of the sewing machine may be and preferably is of the ordinary well known construction, and I would here have it distinctly understood that the improvement is applicable to machines other 40 than sewing machines where the operator is seated during the operation of the machine.

In furtherance of my invention I fix to the end uprights of the main frame 1, hollow bars 2 which are designed to carry the 45 improvement and effect connection of the same to the frame 1. In the present and preferred embodiment of the invention the bars 2 serve as sheaths for endwise adjustable bars 3. The said hollow or tubular 50 bars 2 are longitudinally slotted as indicated by 4, and the bars 3 are provided with pins 5, movable in the slots 4 and adapted to prevent complete withdrawal of the bars 3 from the bars 2. The outer end 55 portion of the bars 3 are connected together

through the medium of a cross rod 6 which is provided with an outward offset 7, Figs. 2 and 3, which is adapted to accommodate it to the treadle of the machine when the attachment is moved inwardly as illustrated 60 by dotted lines in Fig. 1. Fixed on the outer end portions of the bars 3 are upstanding braces 8 in which are arcuate slots 9.

Pivottally connected at 10 to the bars 3 are upright sheaths 11 which are provided at 65 their lower ends with wheels 12 adapted to move on a floor or other surface. The said sheaths 11 are arranged alongside the braces 8 and are provided with threaded projections 13, disposed in the arcuate slots 9, and 70 equipped at the outer sides of the braces 8 with nuts 14. Manifestly when the nuts 14 are loosened the sheaths 11 may be inclined as desired or may be arranged in vertical positions, after which the sheaths may be 75 adjustably fixed by tightening of the nuts 14. The sheaths 11 are slotted as indicated by 15 to receive pins 16 on vertically adjustable toothed shanks 17, and so as to prevent complete withdrawal of the shanks 17 from 80 the sheaths 11. To adjustably fix the shanks 17 in the sheaths 11, I equip each sheath 11 with a spring pressed dog 18. On the upper ends of the shanks 17 are brackets 19, and 85 hinged to the outer ends of the horizontal portions of the said brackets 19, as indicated by 20 is a seat 21. When the improvement is positioned for use as shown by full lines in Fig. 1 the seat 21 bears on the brackets 19 throughout the length of the said 90 brackets. When, however, the movable parts of the improvement are pushed under the top of the sewing machine as shown by dotted lines in Fig. 1, the seat 21 is adapted to ride up on the fly wheel 22 of the machine; it being understood in this connection 95 that the seat 21 will assume a position above the wheel 22 and also above the belt when a belt is mounted on said wheel, and that the adjacent bracket 19 will be relatively arranged to avoid the said belt.

It will be apparent that when the moving parts of the seat construction are in the positions shown by dotted lines in Fig. 1 the floor space occupied will be materially diminished. When the seat construction is to be used, the moving parts are drawn out to the full line position shown in Fig. 1 when the seat 21 will be adequately supported by the wheels 12 and without the 110

imposition of undue weight or strain on the carrying bars 3. It will also be observed that the seat 21 may be quickly and easily adjusted as to height and as readily adjustably fixed against accidental downward movement. Very little effort is required to move the movable parts of the improvement to and from the full line position shown in Fig. 1.

10 Extending between the rear ends of the bars 2 is a rod 2^x. This rod 2^x also extends through the frame uprights 1 and is equipped with nuts 3^x and 4^x, Figs. 1 and 3, disposed at opposite sides of the frame uprights 1. By adjusting the said nuts the said frame uprights 1 may manifestly be adjustably fixed in such spaced relation as to assure free sliding movement of the seat.

Connected by the pins 16 to the shanks 17 20 is a cross brace 23, the end portions of which are disposed vertically and are adapted to slide at the inner sides of the vertical sheaths 11. The said cross brace 23 is fixedly connected to the brackets 19 at points immediately below the seat 21. It will be apparent that by reason of the employment of the braces 23 and 24 the vertically adjustable means supporting the seat 21 is rendered 25 stiff and strong.

30 Having described my invention, what I

claim and desire to secure by Letters-Patent, is:—

1. In a seat construction for sewing and other machines, the combination of slideable bars, upright supports pivotally connected 35 at intermediate points in their lengths to said bars, wheels carried by the lower arms of said supports, upright braces on the bars and alongside the said supports, and means to adjustably fix the supports to said braces. 40

2. A seat construction comprising slotted hollow bars adapted to be affixed to the frame of a sewing or other machine, bars slideable in said hollow bars and having pins disposed in the slots thereof, a cross rod 45 interposed between and connecting the slideable bars and having an intermediate outwardly directed offset portion, braces on the slideable bars and having arcuate slots, sheaths pivotally connected at intermediate 50 points in their lengths with the slideable bars and having slots, dogs on the upper portions of said sheaths, wheels on the lower arms of the sheaths, rack bars disposed in the slots thereof, brackets carried by the rack bars, and a seat hinged to the outer end portions of said brackets.

In testimony whereof I affix my signature.

ELBERT B. McCLURD.
